Application June 25, 1954, Serial No. 31,170

Term of patent 7 years

(Cl. D62—2)

Fig. 1

The dominant feature of the design resides in the closure cap portion illustrated in solid lines.

I claim:

The ornamental design for a drop dispensing bottle, as shown and described.
